SPINNING FRAME

Henry A. Owen, Lawrence, Mass., assignor to
Davis & Furber Machine Company, North
Andover, Mass., a corporation of Massa-
chusetts

Application February 26, 1935, Serial No. 8,253

5 Claims. (Cl. 118—41)

This invention relates to a spinning frame of the ring type in which a row of cooperating rings and spindles is provided at each side of the frame.

The object of the invention is to provide a simple and efficient means of adjustment which will secure the vertical alignment of the rings and spindles and maintain this vertical alignment as the rings and spindles move vertically with respect to each other as required in the 10 operation of the frame.

The nature and objects of the invention will appear more fully in the accompanying specification and drawings and will be particularly pointed out in the claims.

15 The invention is illustrated in a preferred form as embodied in a spinning frame of the general type of construction shown in the patent to Owen, No. 1,842,565, granted January 26, 1932. In such a spinning frame the spinning rings are mounted 20 on rail sections at each side of the frame in a fixed vertical position while the spindles are mounted on rail sections at each side of the frame which in turn are mounted upon vertically movable transverse arches so that the spindles move 25 vertically to cooperate with the rings in the spinning operation but, so far as the broader aspects of the present invention are concerned, it is immaterial which of these elements are stationary and which are vertically movable because it is 30 only the relative vertical movement between the rings and the spindles which is essential.

As the present invention is concerned with only one feature of the spinning frame, and as the general construction and operation of such spinning 35 frames are illustrated in the aforesaid patent and are well known and familiar to those skilled in the art, it is only necessary here to illustrate and describe those portions of a spinning frame with which the invention is particularly concerned.

40 In the drawings:

Fig. 1 is a side elevation partially in vertical cross section of a portion of the spinning frame embodying the invention with many of the parts removed.

45 Fig. 2 is a view in vertical cross section looking toward one end of the spinning frame also with many of the parts removed.

Fig. 3 is a detail in end elevation and partially 50 in vertical cross section and partially broken away showing that portion of the spinning frame with which the invention is particularly concerned.

55 Fig. 4 is a detail in side elevation of one of the bushings employed.

Fig. 5 is a detail in transverse cross section taken on the line 5—5 of Fig. 4.

In the construction illustrated the relative vertical movement between the spindles and rings is effected by mounting the rings stationary and moving the spindles bodily vertically, although the invention is equally applicable to a spinning frame in which the ring rail is moved with respect to the spindles.

A spinning frame comprises end sections, one 10 of which is shown at 1, connected by suitable beams or girts such as 2, 3 and 4 extending lengthwise of the entire frame with suitable intermediate vertical supports 5.

The rings are supported on rail sections and 15 the spindles are also supported on rail sections, the number of such rail sections depending upon the length of the spinning frame.

At each side of the frame vertical guide rods 6 are mounted, in this case on the girts 2. Usually there are two of these vertical guide rods for each rail section at each side of the frame. These guide rods 6 are shown as secured by set screws 7 in socketed bases 8 mounted on the girts 2. Upon the upper ends of the guide rods the ring rail sections 9 are rigidly mounted and the spinning rings 10 are mounted in the usual manner concentric with apertures spaced longitudinally of the ring rail sections 9 as required by the number of spinning elements.

Beneath each ring rail section 9 is provided a spindle rail section 11 mounted to slide vertically on the guide rods 6 and on this spindle rail section are mounted the required number of spindles 12 in the required spaced relation to cooperate with the spinning rings 10. The spindle rail sections disposed at opposite sides of the frame are connected by transverse arches 13, one for each oppositely disposed pair of vertical guide rods. It will thus be seen that when the transverse arches move up and down, the two spindle rail sections, one at each side of the frame, to which the transverse arches are connected are moved up and down to effect the required vertical movement of the spindles with respect to the 40 rings.

The upward vertical movement is usually effected by flexible supporting members 14 connected respectively to points adjacent the ends of the transverse arches 13. These flexible supporting members extend up over idler rolls 15 journalled on the girt 4 and are connected to a main flexible support 16 extending over an idler roll 17 journalled on the girt 4 and thence to suitable lifting means. Counterbalancing weights 18 supported by flexible connectors 19 extending 55

over idler rolls 20 journaled on the girt 4 serve to counterbalance the weight of the transverse arches, spindle rail sections, spindles, etc.

The spindles, as usual, are provided with whirls 21 and are driven by endless bands 22 extending to suitable driving means and deflected into alignment with the whirls by idler rolls or drums 23 mounted on shafts 24 supported by brackets 25 from the transverse arches.

- 10 It will thus be seen that each vertically movable section of the frame comprising the two transverse arches 13, the two spindle rail sections 11, one at each side of the frame, the two rows of spindles carried by the respective spindle rail sections, the yarn receivers or bobbins carried by the spindles and the deflecting rollers or drums 23 with the bands running to the various whirls is of very considerable weight. This entire section must move uniformly and accurately vertically 15 upward and downward at each traverse during the spinning operation in order that the yarn may be led uniformly and evenly onto each of the several yarn receivers or bobbins supported on the spindles. The upward motion, as already 20 pointed out, is obtained from the flexible supporting elements 14 while the downward motion is usually effected by gravity.

In order that the required uniform and accurate movement be obtained and that the spindles and rings during this movement shall be maintained in accurate vertical alignment, it is necessary that the effective length of the transverse arches shall be accurately effected and maintained and that the guide rods shall remain 30 throughout the operation in vertical position. Moreover, this result must be secured notwithstanding the strong pull inward toward the center of the machine exerted by the driving bands 22 on the spindle whirls.

- 40 In this invention a bushing is provided on each vertical guide rod 6 and extends through the spindle rail and transverse arch. This bushing at one end, and preferably at both ends of each transverse arch, is constructed and employed in 45 the present invention as the means for securing the required adjustment for maintaining the vertical position of the guide rods and the vertical alignment of the spindles and rings. In the preferred construction illustrated, the 50 construction is the same at each end of each transverse arch. For this purpose each bushing, one of which is shown separately in Figs. 4 and 5, is provided with a central bore 26 having a close sliding fit on the guide rod 6. At its lower 55 end the bushing is provided with a hexagonal head 27 resting against the bottom of the transverse arch 13. The section 28 of the bushing which extends through the transverse arch 13 is circular but eccentric with respect to the bore 26, while the section 29 of the bushing which 60 extends through the spindle rail section 11 is concentric with the bore 26. At its upper end the bushing is shown threaded at 30 and a nut 31 is mounted on this threaded portion. A lock 65 washer 32 is interposed between the nut 31 and the top of the spindle rail section 11.

It will thus be seen that no matter what the rotary position of the bushing may be, the spindle rail section 11 is maintained in fixed 70 transverse relation to the guide rod 6 and thus the spindles and rings are maintained in vertical alignment. But by rotating the bushing the effective length of the transverse arch 13 is adjusted with respect to the spindle rail sections 75 11 and the vertical guide rod 6 to secure under

all circumstances the required relative position of the parts necessary to maintain the guide rod 6 vertical and allow free vertical movement of the bushings on the guide rods. When each bushing has been rotarily adjusted as required, 5 the nut 31 is turned up, thus securely locking the bushing, the spindle rail section and the transverse arch together in adjusted position.

The required adjustment to secure accurate movement in vertical alignment of the spindles 10 and rings is thus readily secured and if, during the operation of the spinning frame, owing to the breakage of one or more of the flexible supporting members 14 or for any other reason the spindle rail sections drop, or if the flexible supporting members stretch, or if anything occurs 15 to disturb the required alignment, a readjustment is readily effected to restore the alignment by means of these bushings.

Having thus described the invention, what is 20 claimed as new, and desired to be secured by Letters Patent, is:

1. A spinning frame comprising a plurality of vertical guide rods at each side of the frame, a plurality of transverse arches, a pair of ring rail sections one at each side of the frame, a pair of spindle rail sections one at each side of the frame, one pair of said rail sections being rigidly supported on the guide rods, the other pair of said rail sections being supported on the 30 ends of the transverse arches, a bushing on each guide rod the bore of which has a sliding fit on said rod, one section of said bushing being concentric with the bore and journaled in the arch supported rail section and another section of 35 said bushing being eccentric with the bore and journaled in the end of the transverse arch, and means for locking each bushing in rotary adjusted position whereby the arch supported rail sections may be accurately adjusted relatively to the arches 40 to maintain the vertical alignment of the ring and spindle rail sections.

2. A spinning frame comprising a plurality of vertical guide rods at each side of the frame, a plurality of transverse arches, a pair of ring 45 rail sections one at each side of the frame, a pair of spindle rail sections one at each side of the frame, one pair of said rail sections being rigidly supported on the guide rods, the other pair of said rail sections being supported on the ends 50 of the transverse arches, a bushing on each guide rod the bore of which has a sliding fit on said rod, one section of said bushing being concentric with the bore and journaled in the arch supported rail section and another section of said 55 bushing being eccentric with the bore and journaled in the end of the transverse arch, each bushing having a head at one end and a nut threaded on the other end for clamping the rail section and arch together and locking the 60 bushing in rotary adjusted position whereby the arch supported rail sections may be accurately adjusted relatively to the arches to maintain the vertical alignment of the ring and spindle rail sections.

3. A spinning frame comprising a plurality of vertical guide rods at each side of the frame, a plurality of transverse arches, a ring rail section at each side of the frame rigidly mounted on the upper ends of the vertical guide rods, a 70 spindle rail section at each side of the frame supported on the ends of the transverse arches, a bushing on each guide rod, the bore of which has a sliding fit on said rod, one section of said bushing being concentric with the bore and jour- 75

nalled in the spindle rail section and another section of said bushing being eccentric with the bore and journalled in the end of the transverse arch, and means for locking each bushing in 5 rotary adjusted position whereby each spindle rail section may be accurately adjusted relatively to the arches to maintain the vertical alignment of the spindle rail section with the ring rail section.

10 4. A spinning frame comprising a plurality of vertical guide rods at each side of the frame, a plurality of transverse arches, a pair of ring rail sections one at each side of the frame, a pair of spindle rail sections one at each side of the frame, one pair of said rail sections being rigidly supported on the guide rods, the other pair of 15 said rail sections being supported on the ends of the transverse arches, a bushing on each guide rod at one side of the frame the bore of which has a sliding fit on said rod, one section of said bushing being concentric with the bore and journalled in the spindle rail section and another section of said bushing being eccentric with the bore and journalled in the end of the 20 transverse arch, means for locking each of said bushings in rotary adjusted position, and a bushing on each guide rod at the opposite side of the frame mounted in the arch and the arch sup-

ported rail section and having a sliding fit on said rod whereby the arch supported rail sections may be accurately adjusted relatively to the arches to maintain the vertical alignment of the ring and spindle rail sections.

5 5. A spinning frame comprising a plurality of vertical guide rods at each side of the frame, a plurality of transverse arches, a ring rail section at each side of the frame rigidly mounted on the upper ends of the vertical guide rods, a spindle rail section at each side of the frame supported on the ends of the transverse arches, a bushing on each guide rod at one side of the frame, the bore of which has a sliding fit on said rod, one section of said bushing being concentric with the bore and journalled in the spindle rail section and another section of said bushing being eccentric with the bore and journalled in the end of the transverse arch, means for locking each of said bushings in rotary adjusted position, 15 and a bushing on each guide rod at the opposite side of the frame mounted in the arch and the supported spindle rail section and having a sliding fit on said rod whereby the spindle rail sections may be accurately adjusted relatively 20 to the arches to maintain the vertical alignment of the ring and spindle rail sections. 25
